UNITED STATES PATENT OFFICE.

JOHAN BERNHARD, OF NEW YORK, N. Y.

MECHANICAL WINDOW CLEANER.

Application filed April 28, 1927. Serial No. 187,135.

The main object of the invention is to provide a window cleaning device which has a swab which is reciprocated vertically by a hand operated crank arm, and is adapted to be used for cleaning the outer surfaces of a window pane from within the room thus eliminating the necessity of one to step on the sill of the window, in this way preventing possible injury or the danger thereof. Another object of the invention is to provide a window cleaning apparatus which is provided with a swab which reciprocates vertically and is also provided with a drying blade mounted on the swab which remains inactive while the swab is normally operating and is rotated to operative position at the same time that the swab is moved to the inactive position by the operation of a cable which is located at a convenient position for the operator who must constantly rotate a crank which moves the swab mechanism.

The above and other objects will become apparent in the description below in which characters of reference refer to like-named parts in the drawing.

Referring briefly to the drawing, Figure 1 is a top plan view of the window cleaner.

Figure 2 is an enlarged sectional elevational view through the window cleaner carriage showing the means for reciprocating the cleaner swab.

Figure 3 is a front elevational view of Figure 1 showing the device supported on one end of the platform.

Figure 4 is a side elevational view of the window cleaner.

Figure 5 is a partly sectioned side elevational view of the swab tipping mechanism, the view showing the swab in operative position.

Figure 6 is a side elevational view of the swab tipping mechanism, showing the swab tipped and the dryer blade in operative position.

Figure 7 is a fragmentary view of Figure 6 showing the swab in operative position.

Referring in detail to the drawing, the numeral 10 indicates a flat plate which may be of a length somewhat less than the width of the window on which the device is to be used, and serves as the platform on which the remainder of the device slides. At the corners of the platform studs 11, threaded throughout their length, are mounted, and each stud has a pair of wing nuts 12 engaged thereon. A pair of guard rails 13 and 14,

joined at their ends, have their ends seated on one of the wing nuts 12 of each pair, and the rails may be adjusted vertically along the length of the threaded studs 11 to suit the needs required for overcoming any obstructions on the window frame. The guide rails are of hollow construction having an upper and lower ledge between which rollers 15 are positioned. These rollers ride the entire length of the guide rails and support a movable carriage 16 which projects above the guide rails.

A movement carrier 17 is mounted on the carriage and is provided with a pair of slots 18 which are positioned on each side of the carrier and receive screws 19 on which guide plates 20 are mounted, the plate resting partly in the slots 18 and serve as a guide for the carrier, which is slidable across the carriage.

A pair of upright guides 21 and 22 have their lower ends secured to the carrier 17 and are connected at their upper ends to a block 23. Between these upright guides a worm 25 having a helical channel 26 is positioned. The upper end of the worm 25 is journaled in the block 23 and its lower end is seated in a thrust bearing 27 which rides on a complementary raceway 28. The lower end 29 of the worm extends below the floor 30 of the carrier. This floor 30 is raised above the portion of the carrier having the slots 18, the space therebeneath forms a housing 31 in which the worm rotating mechanism is located. The end 29 of the worm 25 has a bevel gear 32 attached thereto and is positioned within the housing 31 and concealed from view.

One end of a tube 33 extends to the carrier 30 and its extreme end terminates in a sleeve 36 which is secured directly to the carrier. This tubing has a spindle 34 rotatably mounted therein which has a bevel pinion 35 secured to its end, the pinion being adapted to lie in mesh with the bevel gear 32. Said spindle is rotatably supported in a bearing block 37, which latter depends from the floor of the carrier and is rigidly secured thereto.

The spindle 34 has a bevelled pinion at its opposite end which is indicated by the numeral 37 and this pinion lies in mesh with a bevel gear 38 on which a crank arm 39 is mounted. The tube 33 extends beyond the bevel gear 38 and has a handle 40 fixed to its extreme end, as is indicated in Figure 4.

A block 24 is slidable between the guides 21 and 22 and has the worm 25 passing there-

2
through, the block having a member engaged in the helical groove or channel 26 so that as the worm is rotated the block 24 will be raised or lowered according to the direction 5 of rotation of the worm. The block has a pair of arms 41 and 42 extending forwardly therefrom whose ends are spaced apart from each other and have a swab 43 pivotally mounted between them. This swab consists 10 of a hollow container which is adapted to fill with water after a cover 44 is opened. The outer face of the container has a pad 45 mounted in holes thereon so that communication is had with the chamber in the container 15 and the pad. When the pad is positioned vertically on the swab body a rubber dryer plate 46 is mounted in a channel and depends from the bottom of the container, the channel member being indicated by the numeral 20 47. This dryer blade is adapted to be rotated to the position that the swab assumes by a mechanism which will be hereinafter described.

A lever 48 is pivoted intermediate its 25 length on a stud 49 which is positioned between the arms and anchored on the latter. This lever is bent upwardly intermediate its length and at the extremity of this upwardly bent end a hinge sleeve 50 is formed. A link 51 is hingedly connected to the sleeve 50 at one end and the opposite end is similarly connected to the hinge plate 53 which is mounted on the side of the swab cover 44. The opposite end of the lever 48 extends toward the block 24 and has one end of a coil spring 54 secured thereto, the spring extending downwardly and being anchored to the lower end of the block 24 by any desirable means. An ear 55 extends downwardly from the lever 48 and is positioned or located where the inclined portion meets the horizontal portion thereof. This ear has a hinge ear 56 constructed at its lower end. The spring is adapted to normally retain the 40 surface of the swab body having the pad 45 thereon in a vertical plane, as is indicated in Figure 5.

At the top of the member 23 a short curved lever 57 is pivotally mounted in the 50 bifurcated portion of a lug which surmounts said member 23 and indicated by the numeral 58. This lever is normally retained in substantially upright position by a coil spring 59 which has one end secured to the lever 57 and the other end secured to the block 23. A shifter bar 60 is pivotally suspended from the lever 57 and extends downwardly behind the worm 25 to the carrier floor 30. Two legs 61 pass thru openings 62 formed 55 in the block 24 and at one end are joined by a brace 63 which has a loop 63' formed intermediate its length thru which passes the shifter bar 60, the loop being slideable on the shifter bar thruout the length of said 60 bar. The lower end of the shifter bar is

70 pivotally mounted on the end of a pivoted short lever 64, the opposite end of the latter being pivotally secured to the roof 30 of the carrier. A cable 65 is connected to the pin 75 which pivotally joins the shifter bar to the lever 64. This cable passes around a pulley 66 which latter is rotatably mounted on the floor 30 of the carrier and thence passes into the housing 31 and then into a tube 67 which terminates at a position adjacent the handle 75 80 40 from which end the cable extends somewhat so that it may be manipulated.

The device is adapted for use in cleaning the outside surfaces of window panes. The platform 10 has a dimension slightly less than the width of the window frame and has a carriage 16 mounted on rollers 15, movable thereon. This carriage supports a carrier 17 which is slideable transversely 85 across the carriage so that the swab may be moved toward or away from the surface of the window pane. By rotating the crank 39, the gear 38 is turned. This transmits rotation to the pinion 37 which in turn rotates the spindle 34 and pinion 35, the latter being mounted on the end of the spindle within the housing of the carrier. The worm 25 having the bevel gear 32 at its lower end is rotated by the rotating spindle and moves the feeder block (to which it is engaged) 90 upwardly or downwardly as desired.

I claim:

1. In a window cleaner, a flat platform, rails adjustably mounted on said platform, a carriage movable along said rails, wheels on said carriage housed and movable in said rails, a carrier slideable in said carriage transversely, vertical U-shaped guides on said carrier, a rotatable worm located between said guides, a block engaging said worm and being raised and lowered thereby, a swab body mounted on said block, a dryer plate located at one corner of said body, means for tilting said body to rotate the dryer plate 90 degrees, and means for rotating said worm to raise and lower the swab body.

2. In a window cleaner, a flat platform, rails adjustably mounted on said platform, a carriage movable along said rails, wheels on said carriage housed and movable in said rails, a carrier slideable transversely across said carriage, spaced-apart guides extending vertically and mounted rigid on said carrier, a cylindrical worm rotatable between said guides having a helical channel therein, a block slideable between said guides having the worm passing therethrough and being raised and lowered by the latter, a swab body rotatably mounted on said block, a pad being located at the side of the swab body when the latter is in normal position, a dryer plate on the swab body normally in depending position, and manually retractable means engaging the brush body for tilt- 120 125 130

ing the brush body 90 degrees at any position along the length of the worm.

3. In a window cleaner, a flat platform, rails adjustably mounted on said platform, a wheeled carriage movably mounted on said rails, a carrier slidably mounted on said carriage having a pair of guides spaced apart extending vertically therefrom, a worm rotatable between said guides, a block engaging said worm and movable vertically between said guides, a swab body rotatably supported on said block having a dryer plate mounted thereon, said plate being normally in suspended position, means for rotating the brush body 90 degrees to shift the dryer plate to the side position, comprising a

curved lever mounted above said worm, a coil spring normally retaining said lever in upright position, a shifter bar suspended from said lever, a lever fixed pivotally on 20 said carrier and pivotally connected to the shifter bar, hinged member connected hingedly to the swab body, and wires connected to the hinge members and slidably connected to the shifter bar, said wires passing thru the block, and a cable connected to the shifter bar for pulling the latter downwardly to rotate said lever to shift the shifter bar farther from the worm to pull on said wires and rotate the swab body. 25

In testimony whereof I affix my signature.

JOHAN BERNHARD.
